(57) **CLAIM**

The ornamental design for a decorative shoe accessory, as shown and described.

DESCRIPTION

FIG. 1 is a rear perspective view of the decorative shoe accessory showing my new design;

FIG. 2 is a front perspective view thereof;

FIG. 3 is a front elevational view of the decorative shoe accessory removed from the shoe;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a front elevational view of another embodiment of the decorative shoe accessory of FIG. 1;

FIG. 10 is a rear elevational view thereof;

FIG. 11 is a top plan view thereof;

FIG. 12 is a bottom plan view thereof;

FIG. 13 is a right side elevational view thereof;

FIG. 14 is a left side elevational view thereof;

FIG. 15 is a front perspective view of the embodiment illustrated in FIG. 1; and,

FIG. 16 is a front perspective view of the embodiment illustrated in FIG. 9.

The portions of the Figures shown in broken lines are for illustrative purposes only and form no part of the claimed design.
